WRINGER MOP STRUCTURE

Joseph H. Trindl, Chicago, Ill.

Application June 13, 1950, Serial No. 167,840

5 Claims. (Cl. 15—119)

This invention relates to improvements in wringer mop structures and more particularly relates to such a structure wherein the mopping, or cleaning element is formed from a block of compressible material which may be squeezed dry without touching the cleaning element with the hands.

Heretofore, various forms of wringer mops using a mopping or cleaning element formed from a block of compressible cellulose material have been in use. The present mops of this type, however, have had certain disadvantageous features in that it has been difficult to provide a wringer which will completely squeeze the mop element so as to expel the dirty water therefrom, such former wringers usually squeezing a large portion of the water into the mop element and leaving an objectionable amount of dirty water in the mop element which cannot be expelled except by washing and by a number of wringing operations. This is particularly apparent with the types of wringer mops which comprise two hinged plates having the cleaning element secured thereto. One reason for this is that when wringing the mop by pivotally moving the plates toward each other, to press out the water, there will be a congested zone adjacent the hinge resulting in an excessive amount of pressure on the cleaning element near the hinge with insufficient pressure toward the outer edges of plates to expel the water from the edges of the mopping element. This excessive pressure on the cleaning element near the hinge further not only presses the dirty water into the cleaning element, but the pressure on the element itself is such that it tends to loosen it from its fastening means and materially shortens its life.

By my present invention I remedy the deficiencies heretofore present in wringer mops by so forming the hinged mop plates that excessive pressures are relieved from the mopping element adjacent the hinge of the mop, and the squeezing pressure is toward the fastening of the cleaning element to the mop plates.

An object of my invention is, therefore, to provide a new and improved form of hinged type wringer-type mop so arranged as to relieve excessive pressures from the mop element near the hinge of the mop and to squeeze the mop element toward the mop plates during the wringing operation.

A further and more detailed object of my invention is to provide a new and improved form of hinge type cellulose sponge wringer mop utilizing two mop plates of an arcaute formation having the mop element secured to a concave portion thereof at laterally spaced points so as to relieve congestion and excessive pressures on the mop element at the hinge of the plates.

Another object of my invention is to provide a more efficient and simpler form of hinge-type mop than formerly so arranged that the wringing operation may be effected by a simple link and lever arrangement operated from a point remote from the mop, so as to avoid the necessity of stooping to wring the mop over a pail.

A still further object of my invention is to provide a novel and improved form of hinge type wringer mop

2

wherein excessive pressures on the mop element adjacent the hinge are reduced by longitudinally separating the mop along the hinge, and by locating the axis of the hinge within the boundaries of the mop element.

5 These and other objects of my invention will appear from time to time as the following specification proceeds and with reference to the accompanying drawings wherein:

On the drawings:

10 Figure 1 is a view in side elevation of a mop constructed in accordance with my invention;

Figure 2 is a view somewhat similar to Figure 1, but showing the mop head hinged to squeeze dirty water from the mop element;

15 Figure 3 is an enlarged rear end view of the mop shown in Figure 1;

Figure 4 is an enlarged plan view of the mop shown in Figure 1 with the handle thereof broken away;

20 Figure 5 is an enlarged fragmentary transverse sectional view taken substantially along line V—V of Figure 4; and

Figure 6 is a fragmentary transverse sectional view of the mop drawn to the same scale as Figure 5 and showing the mop plates in an extreme closed position for squeezing water from the mop.

25 In the embodiment of my invention illustrated in the drawings, a hinged mop head 10 is shown as comprising two hinged mop plates 11 and 12 having a mop element 13 secured thereto adjacent the outer margins thereof. The mop plates 11 and 12 are each of an arcaute formation, as will hereinafter be more clearly described as this specification proceeds and interleave at their adjacent ends. The interleaving portions of said plates are herein shown as being curved downwardly at a relatively sharp angle and as being turned inwardly to form substantially cylindrical bearings for a hinge pin 14, connecting said mop plates together. A hollow handle socket 15 is herein shown as being secured to the forward mop plate 12 and as extending rearwardly therefrom in an angular direction. A handle 16 is carried by said socket in a usual manner. It should here be understood that the socket 15 need not be secured to said front plate, but may be secured to said rear plate as well.

30 Two spaced ears 17—17 are shown as extending upwardly from the mop plate 11 within a hollow recessed under portion 19 of the handle socket 15. A nut and bolt 20 is shown as being mounted in the spaced ears 17—17 to form a pivotal pin, pivotally connecting a rounded inwardly and upwardly turned end 21 of a wringer link 22 to the mop plate 11. The opposite end of the link 22 extends between the furcations of a bifurcated portion 23 of a wringer lever 24 and is pivotally connected thereto intermediate its ends, as by a nut and bolt 25. The wringer lever 24 is herein shown as being pivotally mounted to the handle adjacent the ends of the furcations thereof on the legs of a substantially U-shaped bracket 27, by means of a nut and bolt indicated generally by reference numeral 29. The hanger 27 may be secured to the handle as by a machine screw 30 extending therethrough and threaded within the hanger and locked thereon in a suitable manner, such as a lock nut (not shown), or by peening over the end of the screw.

35 It should here be noted with reference to Figures 1 and 3 that when the mop plates 11 and 12 are in an extended position, the wringer link 22 extends between the furcations of the operating lever 24 and that the points of pivotal connection of said link to the hinge plate 11 and the operating lever 24 are off-center with respect to the pivotal axis of said operating lever, thus providing a self-locking wringing means which holds the mop plates in extended relation with respect to each other during

the mopping operation. It should further be noted that the ears 17-17 are close to the hinge of the plates and extend within the recessed hollow portion of the mop socket 15, so as to permit the use of a single link and lever to pivot the mop plates with respect to each other and squeeze water from the mopping element. This arrangement also maintains the operating parts for the wringer within the limits of the mop and thus avoids the scratching of the furniture or base boards during the mopping operation.

Referring now in particular to the novel form of the mop plates 11 and 12 and the mounting of the mop element 13 thereon, each of said mop plates is herein shown as being formed in transverse section about an arc of relatively long radius for a greater portion of the width of the mop plate and about a substantially shorter radius adjacent the inner sides of the mop plate and the hinge pin 14. This recesses said hinge pin and the interleaving hinged portions of said plates beneath the top surface of the mop element and causes said plates to draw away from the center of the mopping element, during the wringing operation, and prevents congestion of the mopping element in the region of the hinge, and thus relieves the mopping element from excessive pressures in this region. It also causes the wringing pressures on the mop element to be adjacent the outer ends of the mop element in directions toward the mop plates.

The mop element 13 may be made from a block of compressible material such as a natural, or cellulose sponge, or any other like material, and is herein shown as comprising a rectangular block of cellulose sponge which is separated longitudinally adjacent the upper portion thereof and as having the hinge connecting the plates 11 and 12 together recessed therein. The longitudinal separation of the sponge may be formed merely by slitting the sponge along its length at a depth slightly greater than the depth of the hinge, but is herein shown as being a slot extending longitudinally along the top of the sponge. A fabric backing member 31 is shown as extending therein and as being secured thereto and extending beyond opposite sides thereof to the edge of the sponge.

The fabric backing member 31 may be made from canvas, or any other suitable material and is preferably cemented to the slot and to the top of the sponge. The backing member may extend beyond the lateral edges of the sponge around cords or rubber bumpers 32 at its opposite ends, and may be sewed adjacent the inner margins of the cords or bumpers to enclose the cords or bumpers and position them beyond the edges of the mop, and form a protecting means therefor. The backing member 31 may then extend over the top of the fabric toward the center thereof. Longitudinally extending fastening strips 33-33 may be cemented between the layers of the fabric, to form a means for securing the sponge to the hinge plates 11 and 12.

The strips 33-33 may be made from metal or any other suitable material, and have longitudinally spaced threaded members 34-34 extending upwardly therefrom. The threaded members 34-34 extend through the overlapping fabric and through suitable apertured portions in the mop plates 11 and 12 and have knurled nuts 35-35 threaded on the outer ends thereof. The nuts 35-35 abut the tops of the plates 11 and 12 to secure the mop element thereto. The arrangement of the strips 33-33 is such that tightening of the nuts 35-35 draws the mop element into engagement with the concave inner sides of the mop plates 11 and 12 adjacent their outer margins, but allows a certain freedom of movement between said mop element and the concave inner side of said mop plate, adjacent the hinged portion thereof, to aid in relieving the mop element from excessive strain during the wringing operation and to allow floating movement of the interior of said mop element adjacent the hinge, to avoid any tendency to pull the mop

element away from the mop plates 11 and 12 when wringing the mop.

While the fabric 31 is shown as being one piece sewed around the cords 32-32, which form end bumpers for the mop it need not be in one piece and may be made in two or more pieces, with the cords 32-32 sewed to either the upper or lower pieces thereof.

It may be seen from the foregoing that a simplified form of hinge type wringer mop has been provided, so arranged as to relieve the mop element from congestion and excessive internal stresses at the hinge of the mop and squeezing all of the water toward the outer edges of the mop when wringing, and thus enabling the mop to be squeezed substantially dry in a simple operation.

It may further be seen that a simple link and lever arrangement is provided to facilitate wringing of the mop without bending over, and avoiding the usual multiplicity of links and levers heretofore used to position the wringing lever adjacent the operator, and that the operating means for wringing the mop is within the lateral limits of the mopping element when the mop plates are in an extended position, placing the wringing mechanism in such relation that it will not interfere with the mopping operation.

It will be understood that modifications and variations may be effected without departing from the scope of the novel concepts of the present invention.

I claim as my invention:

1. A mop including a mop head having a mop element comprising a block of compressible material secured thereto, a handle extending from said mop head, said mop head including two elongated concave-convex mop plates, hinge means pivotally connecting adjacent sides of said mop plates together for movement about an axis extending longitudinally of the mop head intermediate the sides thereof and including a hinge pin extending longitudinally of the mop plates, each of said mop plates having a portion of the mop element recessed within the concave portions thereof, securing means extending along said mop element at laterally spaced points and securing said mop element to said mop plates adjacent the outer sides thereof, but leaving the central portion of said mop element relatively free from said mop plates, and said mop element having a longitudinally extending recessed portion recessing said hinge means and hinge pin beneath the top surface of said mop element, and the portions of said plates adjacent said hinge means and hinge pin moving away from the mop element during the wringing operation and relieving the mop element adjacent said hinge means from congestion and excessive pressure during wringing thereof.

2. A mop including two elongated mop plates having inner hinged portions and a hinge pin extending through said hinged portions and pivotally connecting said mop plates together, a handle secured to and extending from one of said mop plates, means secured to the other of said mop plates within the lateral limits thereof and operable to pivotally move said mop plates about said hinge pin toward and from each other, said mop plates each being of a concave-convex form in transverse section and the concave portions thereof forming two arcuate recesses

60 on opposite sides of said hinged portions, a mop element comprising an elongated block of compressible material, means detachably securing said mop element to the concave recessed portions of said mop plates at points spaced closer to the outer than the inner margins thereof, said mop element having a recess extending longitudinally therealong and having said hinged portions extending therein beneath the top surface of said mop element when said mop plates are in extended relation with respect to each other, and said hinged portions and hinge pin 65 moving away from said mop element to relieve said mop element adjacent said hinged portions upon pivotal movement of said mop plates toward each other to wring the mop element.

3. A mop including two elongated mop plates, means 70 pivotally connecting said mop plates together for wring-

ing movement, a handle socket secured to and extending from one of said mop plates and having a handle extending therefrom, means partially recessed within the said handle socket and secured to the other of said mop plates for moving said plates in a direction to wring the mop, said plates each being of a concave-convex form in transverse section and the concave portions thereof forming two arcuate recesses on opposite sides of the pivotal axis of said plates, a mop element comprising a block of compressible material secured to said recessed portions of said mop plates at points spaced laterally from the pivotal axis thereof and adjacent the outer margins thereof, said mop element being longitudinally separated intermediate its sides for a portion of its thickness and having the means for pivotally connecting said plates together recessed therein beneath the top surface thereof and affording relief for said mop element and relieving said mop element from excessive pressures adjacent said connecting means during the wringing operation thereof.

4. A mop including two elongated mop plates, a hinge pin pivotally connecting adjacent sides of said plates together, a handle socket secured to and extending from one of said plates, means partially recessed within the base of said handle socket and connected to the other of said mop plates, for moving said plates in a wringing direction and for holding said plates in extended relation, said plates each being of a concave-convex form in transverse section, the concave portions thereof forming two arcuate recesses on opposite sides of said hinge pin, a mop element secured to the recessed portions of said mop plates and having a slotted portion extending therealong and recessing said hinge pin within said mop element, said plates each curving about a relatively large radius of curvature toward their outer sides and curving about a shorter radius of curvature adjacent their adjacent sides and positioning said hinge pin to move away from said mop element during wringing of the mop, and relieving the central portion of said mop adjacent said plates from excessive internal pressures.

5. In a mop, a mop element formed from a block of compressible cellulose material, a mop head having a handle extending therefrom, said mop head comprising two elongated mop plates, interleaving at their adjacent sides, a hinge pin pivotally connecting the interleaving portions of said plates together, said plates each being of a concave-convex form in transverse section, the concave portions thereof forming two arcuate recesses on opposite sides of said hinge pin, said mop element being secured to the recessed portions of said mop plates and having a slotted portion extending therealong and recessing said hinge pin within said mop element, said plates each curving about a relatively large radius of curvature toward their outer sides and curving about a shorter radius of curvature adjacent their adjacent sides and positioning said hinge pin and interleaving sides of said mop plates to move away from said mop element during wringing of the mop, and relieving the central portion of said mop element adjacent said mop plates from excessive internal pressures.
